(57) CLAIM

The ornamental design for a lipstick container as shown and described.

DESCRIPTION

FIG. 1 is a front, right, top perspective view of a lipstick container showing the new design.

FIG. 2 is a rear, left, top perspective view of the lipstick container of FIG. 1.

FIG. 3 is a front, right, bottom perspective view of the lipstick container of FIG. 1.

FIG. 4 is a rear, left, bottom perspective view of the lipstick container of FIG. 1.

FIG. 5 is a front elevation view of the lipstick container of FIG. 1.

FIG. 6 is a rear elevation view of the lipstick container of FIG. 1.

FIG. 7 is a left side elevation view of the lipstick container of FIG. 1.

FIG. 8 is a right side elevation view of the lipstick container of FIG. 1.

FIG. 9 is a top plan view of the lipstick container of FIG. 1.

FIG. 10 is a bottom plan view of the lipstick container of FIG. 1.

FIG. 12 is a front, right, bottom perspective view of the lipstick container of FIG. 1 with the cap removed and the inner lipstick tube removed. The rear, left, bottom perspective

tive views of the cap, the uncapped lipstick container, and the inner lipstick tube are identical, respectively, to the front, right, bottom perspective views of the cap, the uncapped lipstick container, and the inner lipstick tube shown in FIG. 12.

1 Claim, 9 Drawing Sheets
